PROCESS OF PRODUCING GASOLINE AND OTHER HYDROCARBONS FROM COCONUT OIL AND RELATED ANIMAL AND VEGETABLE OILS AND FATS

Sergius Petroff and Anthony E. Prats,
Manila, P. I.

Application May 3, 1946, Serial No. 667,010

1 Claim. (Cl. 260—666)

1

This invention relates to a process by means of which gasoline and other hydrocarbons, including lubricating oil, kerosene, etc., may be produced from vegetable oils and animals fats, and is particularly designed for the production of oils similar to petroleum oils, i. e., essentially hydrocarbon oils, in localities where economic conditions make it justifiable.

While hydrocarbon oils have heretofore been produced in laboratories from vegetable oils, the processes previously have generally embodied a thermal cracking operation (pyrolysis), usually in the presence of various catalysts. In the process of the present invention the production of the hydrocarbon in the first instance at least is apparently not dependent upon any thermo decomposition reaction but upon the utilization of a reaction producing hydrocarbon oils at comparatively low temperatures, thus establishing the high efficiency hereinafter described.

In the process of the present invention, by the process of saponification into glycerin and fatty acid, the fatty acids are converted into lime soap. For this purpose saponification is done most conveniently by reaction with milk of lime. The production of the hydrocarbons is carried out by reacting the lime soap with additional slaked lime in a retort which may be heated to temperatures which may not exceed, say, 625° F. so as to be well below the normal thermal cracking point of oils. We have found that under these conditions the lime soap (which may be represented by the formula $\text{Ca}(\text{RCOO})_2$) undergoes reaction forming hydrocarbons which may be represented by the following:

In the foregoing formula reaction, R represents hydrocarbon radical and accordingly RH as produced by the reaction is the obtained hydrocarbon. The reaction may be carried out to a substantial completion with a full theoretical yield of the desired hydrocarbon. The hydrocarbon oils obtained may be fractionally distilled into products corresponding to the products obtained from petroleum oil, such as gasoline, kerosene, etc., and may be subjected, or certain fractions thereof be subjected to, any usual or preferred type of cracking reaction in order to increase the proportion of gasoline constituent produced by the operation.

In order that the reaction described above shall proceed smoothly and efficiently, we have further discovered that the mass undergoing re-

2

action in the retort should be maintained in a substantially fluid or semifluid state and under continuous mixing. This, we have found, can be effected by adding to the reacting mass of slaked lime and calcium soap a quantity of high boiling oil which may be a fraction of the product of the process produced in some previous operation.

The process of the present invention, together with various further objects and advantages of the invention, will be completely understood from the following description of the preferred forms or examples of the process. We have, therefore, described in connection with the accompanying drawings, the preferred forms of the process.

In the drawings:

Figure 1 indicates an apparatus of the type we have employed for carrying out the process in a batch operation.

Figure 2 indicates a suitable apparatus for carrying out a continuous operation.

In the preferred process of the present invention, the vegetable oil is first split into glycerin and fatty acids or calcium soaps of fatty acids. While this may be accomplished by an autoclave process (or by Twitchell's process) giving a glycerin-water and free fatty acid with a subsequent separation of the fatty acid from the glycerin and its reaction therafter to form lime soap, in the preferred process of the present invention, preferably slaked lime is added to the vegetable oil and the vegetable oil saponified directly to a mixture of lime soap and glycerin. For example, to 75 kilograms of quick lime is added 250 kilograms of water to form milk of lime, after which there is added 500 kilograms of coconut oil. Then with continuous stirring the mass is heated to boiling and then preferably left to stand for about a day for the completion of the saponification reaction. Thereafter the lime soap is filtered and the glycerin contained therein washed out, for example, by repeated portions of warm water.

The lime soap is then ready for the production of the hydrocarbons which may be carried out, for example, in the apparatus shown in Fig. 1 of the drawings. In Fig. 1 of the drawings, 2 generally indicates a retort set in a furnace 3 where the same may be heated by any suitable means. The retort is provided with a stirrer, or a combined stirrer and scraper such as is indicated at 4. The retort 2 is provided with a header 5 communicating with a condenser 6 leading to a re-boiler 7. The re-boiler 7 may be mounted in the same furnace 3, as indicated.

From the re-boiler 7 a line 8 leads to a condenser 9.

In operation of the process as a batch operation, as it was applied in our pilot plant in Manila, the lime soap from the saponification operation was placed in the retort 2. The retort 2 was of size sufficient to handle one-half of the product from 500 kilograms of coconut oil. In the retort there was added about 20% excess powdered slaked lime over and above that required by the formula previously described for the production of the hydrocarbons. In the example being described, this corresponded to about 50 kilograms of lime. There was also preferably added a high boiling point hydrocarbon oil in order to assist in maintaining the contents of the retort 2 fluid. For this purpose about 50 kilograms of high boiling point oil was added from the previous operation. The material in the retort 2 is then heated while being mixed, the mixer 4 turning over three or four revolutions per minute. Distillation of the produced hydrocarbon material starts at temperatures around 200 to 250° C. and continues until the temperature reaches around 500° C. During the process, the vaporized hydrocarbons are partially condensed in the condenser 6 and the condensed materials to some extent re-boiled in the re-boiler 1, which results in the partial separation, at least, of the low and high boiling point oil. The high boiling point oil is retained in the re-boiler 1, while the low boiling point oils, along with some produced steam from the retort 2 passes through line 8 on the condenser 9. The condenser 9 cooling water should be added through line 10 so as to maintain the temperature at about 20° C. in order to effectively condense all of the lighter hydrocarbon materials. These operations of the process did result in substantial, complete recovery of the hydrocarbon component of the lime soaps as hydrocarbon oil.

Now referring to Fig. 2 of the drawings, we have shown a modified form of the apparatus which may be used for a continuous operation. As indicated in the drawings, there is provided a retort 11 slightly tapering towards the discharge end and generally positioned in a horizontal manner, as indicated. The retort is partially divided into a plurality of compartments by the baffles 12 and 13 which in the first compartment illustrated, prevents the movement of liquid or solid material, but allows the overflow of liquid from one compartment to the other compartment. In the last compartment of the retort there is an opening at the lower end baffle 12, as indicated at 14, where any solid residue may pass into the last compartment. A common shaft 15 is provided which mounts a scraper and mixer 16 in each of the compartments of the retort. These scrapers are preferably given a slight pitch so that the scrapers in the last two compartments of the retort will assist in moving the mass in the interior of the apparatus.

To the first compartment there is connected a supply line 17 in which the mixture of melted lime soap, slaked lime, and high boiling point oil may be continuously supplied, and from the last compartment there leads a discharge line 18 for removing any residue from the retort. 19 indi-

cates suitable drive means for the mixer shaft 15 and burners 20 are indicated as provided for each compartment so that separate regulation of the heat thereto may be carried out, if necessary. The temperature in the retort must be gradually raised from 150° C. in first compartment up to 500° C. at the discharge end of the retort.

Each of the compartments is provided with a separate discharge line 21 from the vapors which, if desired, may be separately collected, but we have indicated the discharge lines 21 as connected to the common manifold 22 leading to a condenser 23.

The manner of conducting the reaction in the continuous retort is believed obvious from the description given; materials are continuously supplied to line 17 to produce hydrocarbons continuously, which are in turn condensed in the condenser 23.

Resulting from the reaction taking place in the retort of the present invention, there is provided hydrocarbon oil commonly equivalent to about 97% readily obtainable by the reaction. This hydrocarbon oil includes without alteration by cracking, other means, gasoline constituents together with kerosene, lubricating oil, and high boiling point constituents. In one example of the process, there was produced a so-called light oil compound equivalent to gasoline in boiling point amounting to about 28% of the product, the remaining 72% being heavier oil. The production of the light oil may be increased by cracking the heavy oil.

While the particular form of the process herein described is well adapted to carry out the objects of the present invention, it is to be understood that various modifications and changes may be made, and this invention includes such modifications and changes as come within the scope of the appended claim.

We claim:

A process of producing hydrocarbons, which comprises adding to a lime soap a high boiling point hydrocarbon oil and an excess of slack lime over the stoichiometric quantity required to combine with the lime soap and produce by a double decomposition reaction hydrocarbons and calcium carbonate, heating the admixture to a temperature sufficient to produce such a double decomposition reaction, while vaporizing and removing the produced hydrocarbons and continuously stirring the reacting mixture during such reaction.
